UNITED STATES PATENT OFFICE.

WALTER E. TRUFANT, OF WHITMAN, MASSACHUSETTS.

LAST.

No. 851,968.

Specification of Letters Patent.

Patented April 30, 1907.

Application filed January 6, 1902. Serial No. 88,539.

To all whom it may concern:

Be it known that I, WALTER E. TRUFANT, of Whitman, in the county of Plymouth and State of Massachusetts, have invented certain new and useful Improvements in Lasts, of which the following is a specification.

My invention relates to that class of lasts which are called divided or hinged lasts and are arranged to shorten to facilitate their removal from, or insertion into the shoe, and has for its object to provide adjustment to take up the wear of the parts and to compensate for any inaccuracy in fitting up the parts, and especially to allow the same connecting device to connect different toe parts to the same heel part or different heel parts to the same toe part; and to this end consists of certain improvements which I will now describe and point out in the claims.

20 In this embodiment I show my invention as applied to a last of similar construction to the one described in patent granted to me September 26, 1899, No. 633,741, but it may be applied to other styles of lasts as will be readily seen. In the above mentioned patent the links or members which connect the sections cannot be finished before they are in position as it is impossible in practice by the present method of manufacture to drill the 25 holes in the links and in the sections of the last so that the parts can be afterward assembled, but it is found necessary that the hole for the pivot in one end of one of the links must be drilled after the other parts are all fitted. In the old construction if any of the parts are changed it is necessary to discard one of the links and put in a new one that may be fitted to the parts as reassembled, and there is no way to take up the wear 30 or stretch of the parts. It is well known that the changes in the shape or style of lasts, owing to fashion, are usually made in the toe, and that in a great variety of lasts the heel part will be found to be the same shape. 35 For this reason a connecting device which can be adjusted to different toe or heel parts without further fitting is very desirable, as in that case a new toe part can be made and used with the same heel part and connecting 40 links. As most of the labor and expense of making lasts is in forming the heel parts and the connecting links the saving made in retaining these is very great.

45 In the accompanying drawings, forming a part of this specification, Figure 1 represents

a last in operative position containing my improvements with a part broken away to show a longitudinal vertical section through the center of the last extending from the heel to a point forward of the space occupied by the connecting device. Fig. 2 shows a side view of the metallic heel seat of the last with my adjusting bar. Fig. 3 is a front view of the metal heel seat shown in Fig. 2. Fig. 4 is a perspective view of my curved adjusting bar. Fig. 5 shows a view of the adjusting screws which connect the bar to the heel seat. Fig. 6 shows a section of a toe part containing a modification of my adjusting bar. Figs. 7 and 8 are other views of the bar and link shown in Fig. 6.

In all the figures the same letters of reference refer to identical parts:

a is the toe part of a last divided transversely by the line *l m*, and *b* the heel section.

c is a metal heel seat which extends from the face of the section far enough back to contain the connecting device and jack spindle hole *d* and extends from the top to the bottom of the last. This heel seat contains the recess *e*³ in which the connecting links *e* and *f* work. The link *e* is pivoted or articulated at one end to the toe section *a* in the slot *e*¹ by the pivot pin or rivet *g* and at the other end to the link *f*. One end of the link *f* is pivoted to the link *e* and the other end to the adjustable bar *h*. The heel seat *c* has a segmental slot *h*¹ through the wall on each side of the recess *e*³ which slot extends from near the bottom of the last upward and forward to a point beyond the point at which the link *f* is to be pivoted. At the lower end of the slot *h*¹ is the adjusting screw *h*² threaded to the heel seat, and threaded internally for the screw *h*³. The forked bar *h* is fitted to the slot *h*¹ with the base of the fork resting on the screw *h*² and the screw and bar secured together by the screw *h*³. The sides of the fork and the walls of the heel seat are about the same thickness and the fork extends nearly to the end of the slot. Near the end of the fork are the holes *g*³ *g*² to receive each end of the pivot pin *g* on which the link *f* pivots.

50 In fitting up my improved last the metal work is all finished and assembled before connecting with the wood part of the last. After the wood part of the last is turned and the outside finished it is divided through the line *l m* and the toe section recessed and the

link e secured in place by the rivet or pin g . The heel section of the last is next recessed to receive the metal heel seat c and the wood secured to the heel seat by rivets or otherwise. The sections are then brought together and the links brought to their locked position, after which the screw h^2 is turned backward until the desired tension is obtained on the links when the screw is locked 5 wise. The sections are then brought together and the links brought to their locked position, after which the screw h^2 is turned backward until the desired tension is obtained on the links when the screw is locked 10 and the bar secured by tightening up the screw h^3 , which clamps the parts firmly and securely together. It will be noticed that the bar h is made curved so that any longitudinal movement of it will be sufficiently near 15 in line with the pivots of the links to secure the proper adjustment. The shape of the heel of the last and the position of the jack spindle hole makes it undesirable to extend the bar out to the rear part of the heel, and 20 if the bar was straight and was adjusted from the same point at the heel as the curved bar is adjusted the movement in adjusting it would be nearly normal to the two pivots, so little tightening effect would be secured. By 25 using a curved bar the movement in adjusting is nearer in line with the pivots, and a much more convenient and effective arrangement of the parts is obtained, and the desired adjustment of the parts and tension on 30 the connecting device is readily secured. The last here shown is operated in other respects the same as the one shown and described in my before mentioned patent excepting that the movement of the links in locking and unlocking the sections is reversed which is found more convenient in practice. In this case the last is locked by pressure applied at the point f^1 which forces the heel section down against the toe section and carries the pivot g^1 past the center line of the 35 pivots or articulations g and g^2 , and is unlocked by pressure on the point f^2 which carries the pivot g^1 back by the center line of the pivots and as the links open allows the heel 40 section to slide up on the toe section as shown by the dotted line in Fig. 1.

In case the metal heel seat is not used, or for any other reason it is desired to make the adjustment in the toe section, I provide the 45 modification shown in Figs. 6, 7, and 8 which consists of a bar k to which the link e is pivoted. The adjusting bar k has a cylindrical shank with a hole in the end opposite the pivot threaded to fit the screw k^3 , the other 50 end of the bar has a tenon k^1 which is the same thickness as the link f and fits in between the two sides of the link e and holds the pivot pin g^1 . In applying this bar to the toe part a^1 of a last a hole k^2 is drilled the 55 size of the bar from the end of the recess e^2 on an angle toward the bottom of the last, but this hole is drilled deep enough only to receive the bar and allow for adjustment. Next a hole the size of the shank of the screw 60 k^3 is drilled through to the bottom of the last

and the recess k^4 countersunk to receive the head of the screw, the bar and link is then put in place as shown in Fig. 6 and the parts adjusted by turning the screw k^3 .

It is obvious that there are many modifications, besides the one shown, of my adjusting bar possible without departing from the scope of my invention, and in place of one bar or a forked bar two or more bars or their equivalent could be used if desired.

What I claim as my present invention and desire to secure by Letters Patent is:

1. In a transversely divided last the combination of a toe section, a heel section, a connecting device permanently connected to each section and comprising a plurality of relatively movable members, said connection in the toe section consisting of a bar extending forward toward the bottom of the last, said section containing a recess extending to the bottom of the last to receive said bar, and means for adjusting said bar in said recess.

2. A transversely divided last consisting of a toe-part section and a heel-part section, pivoted members secured to and connecting said sections, an adjustable bar in one section to which one of said members is secured, and means for adjusting said bar.

3. A transversely divided last consisting of a toe-part section and a heel-part section, connecting links pivoted to each of said respective parts, an adjustable bar in one of said parts, one of said links being pivoted to said bar, and means for adjusting the bar.

4. A transversely divided last consisting of a toe-part section and a heel-part section, pivoted members, one of said members being fastened to each of said respective parts, a bar in one section to which one of said members is pivoted which extends away from the other section toward the outside of the last, and means for moving said bar to adjust the tension on said pivoted members.

5. A divided last comprising sections, articulating members connecting said sections the connecting point whereof is adapted to pass the dead center line of articulation to lock the sections, adjusting means by which one of said members is connected to its last part, and means for locking said adjusting means.

6. A multipart last comprising sections, members connecting said sections having vertical movement for separating and drawing together said sections, and means for longitudinally adjusting said members to vary the tension on the parts resulting from said vertical movement.

7. A multipart last comprising a toe section and a heel section, an extensible connecting device composed of members, means for shortening said connecting device, and adjusting means between one of the members of said connecting device and its last part to

vary the effective shortening operation of said connecting device.

8. A multipart last including a toe section and a heel section, a connecting device comprising, a plurality of relatively movable members connected respectively with the complementary parts of said last, and adjusting means between one of said members and its last part by which to vary the relative

shortening movement of said members and thus the connection between the last parts.

In testimony whereof I have affixed my signature, in presence of two witnesses.

WALTER E. TRUFANT.
